JOSEPH B. KISLINGER, OF NEW YORK, N. Y., ASSIGNOR TO MARIE B. KISLINGER, OF NEW YORK, N. Y.

WATCH CONSTRUCTION

Application filed August 20, 1926. Serial No. 130,448.

The main object is to provide a highly ornamental pendant watch which is practical to make and repair and which is durable and reliable.

The watch movement is mounted in a body 5 formed partly or wholly of ornamental material such as rock crystal, precious or semi-precious stones, pearl shell, onyx or glass which may be colored or shaped to represent precious stones. The body is held by a metal 10 band or rim which partially protects it against injury and yet facilitates removal of the body and replacement in case of accident or when it is desired to employ a body of different color or material. The watch movement is enclosed in the usual metal case which 15 in turn fits snugly within the outer body and reinforces it. It also involves improvements in the body ensuring more perfect pieces when made of pressed material such as 20 glass, celluloid, or the like.

The details of the preferred form and some of the modifications which I consider embody features of my invention will be found il- 25 lustrated and described herein.

Fig. 1 is a front view of one form of watch embodying my invention, part being broken away.

Fig. 2 is a side or edge view of the watch.

Fig. 3 is a horizontal sectional view and plan of one form.

Fig. 4 is a vertical sectional detail view of the clamp and pendant on the plane of line 5-5 Fig. 2.

Fig. 5 is a horizontal section of the same on the plane of line 6-6 Fig. 4.

Fig. 6 is a vertical section of another modification.

Fig. 7 is an enlarged section of a modified 40 form of band.

The watch movement 9 may be of any style or shape suitable for the purpose desired, for instance, round, oval, or rectangular.

This movement is enclosed in a metallic 45 case 10 having a dial 11 and a back plate 12 held in place in any suitable manner. The winding stem 13 has a removable tubular extension and a crown 14 adapted to be screwed on to the outer end.

As shown in Fig. 3 the body may consist

of two plates or parts 15 and 16 which are identical, and hence interchangeable. Each plate has a recess or cavity to accommodate part of the watchcase and movement. Each recess has a peripheral shoulder such as 17 and 55 18 to position the dial 11 and case plate 12 respectively. The difference between the thickness of the dial 11 and the case plate 12 is sufficient to leave room enough for the free movement of the hands 19 of the watch and to provide a recess around the edge of the dial in which luminous paint may be placed for illuminating the hands. A groove, passage or channel 20 is provided for the stem 13 and its tubular extension. Each of the parts of the 60 body preferably has a central transparent lens portion 22 which projects outwardly and is bounded by a shoulder 23 of approximately the same diameter as the inner shoulder 18. This not only clearly defines the location of 65 the lens but ensures a uniform pressing action and consequent uniform product when the plates are made of glass or other pressed material.

The outer faces of the plates 15 and 16 are 70 preferably ornamented or provided with facets 24 and inclined toward the edges which are bevelled at 25. The dial 11 and back case plate 12 may be ornamented or engraved if desired. So, also, the inner faces 26 may be 75 ornamented or marked as desired, for instance, with monograms or other legends, symbols, or emblems. The face of the dial may be illuminated, for instance, with luminous paint at 11' either on the dial or on the 80 inner surfaces of the lens 22 around the edges of the recess at 19'.

The rim or band 27 is of V-shaped section metal which fits the bevelled edges 25. The 85 ends 28 and 29 are parallel and shaped to form a bearing for the swivel sleeve 30 which holds the ends together with the band clamped on the body of the case.

A screw socket 31 is provided between the 90 ends and secured to one of the ends so as to prevent withdrawal. The locking screw 32 has a threaded engagement in this socket between the ends so as to eliminate the necessity for a nut. The head of the screw 32 may be 95 large enough to overstand the upper edge of 100

the sleeve 30 or a separate washer 33 may be interposed, if desired. The bow 34 is anchored or pivoted in the walls of the sleeve 30.

The means for securing the parts of the frame together is claimed in my Patent 1,600, 589.

Preferably the enclosing body is tapered at its upper end and the outline of the outer edge is continuously convex so that the band 27 may be clamped smoothly in place.

10 In the form shown in Fig. 6 the body is formed of two plates, the front plate 50 being thicker than the rear plate 51. In this case the crystal or lens 52 is formed separately, 15 and the groove 53 for the winding stem 54 is formed entirely in the back of the main front plate of the body. The band 55 holds the parts together.

15 The outer band, or rim may be split in two pieces such as 60 and 61 which are adapted to snap one within the edge of the other, as is shown in Fig. 7. These two frame pieces fit around the outer edges of the outer body so that when the pieces 60 and 61 are interlocked the frame is held in place.

20 Each of the foregoing forms has its own advantage for different purposes and in different materials. The shape and ornamentation may be varied except as limited by the plain terms of the claims.

25 The double casing provided by the regular metallic watch case fitting snugly within the heavy glass or other non-metallic body part, such as 15, 16 and 40, serves not only to keep out dust and even water (when the stem is properly packed) but the metal and glass reinforce each other to produce an almost indestructible case. The external band 27 or 40, 46 also reinforces the outer body member. These features are of considerable importance especially when it is remembered that the principal purpose is to provide a practical pendant watch which is naturally subjected to very rough usage.

45 I claim:

1. A watch case including a body member having a recess adapted to at least partially enclose a watch movement and having a transparent portion adapted to serve as a crystal therefor and having a recess surrounding said crystal portion adapted to receive a luminous material for illuminating the face of the movement.

2. A watch case body comprising a molded part having a recess with an inner wall and shoulder for supporting a wall of a watch case and having the wall opposite the recess formed to constitute a lens, the outer edge of which is located in line with the inner shoulder.

3. A watch construction comprising a watch movement, a metallic case enclosing said movement, a glass body formed of two interchangeable parts each having a recess containing one half of the metallic watch case,

each part having a thick arched transparent wall opposite said recess, said watch case reinforcing the glass body interiorly and an outer band surrounding the edges of the body and protecting the same.

4. A watch comprising a metallic casing, a movement within the casing, a face external to the casing, a pair of non-metallic members, larger than said casing, means for clamping said members about said casing, including a circumferential metal band adapted to engage both said members, means for winding said movement extending through said band to the exterior and a supporting ring attached to said band, said winding means preventing the rotation of the movement within said non-metallic members.

5. A watch comprising a movement having a face and hands, a non-metallic body member in front of said movement, having a transparent portion opposite said movement, a second body member back of said movement, a metal band having substantially straight end portions making an acute angle with each other and a central portion tangent to both of said portions, said body having periphery conforming to the shape of the said band, and means for clamping said end portions together to draw said band around said body, whereby strain is imposed upon said band in the direction of its length, to hold said parts tightly together.

6. A watch case comprising, in combination, a pair of members adapted to be placed in juxtaposition, and having a cavity between the juxtaposed faces, a watch movement adapted to be placed within said cavity, a channel in said juxtaposed faces adapted to afford communication between said chamber and the exterior, a stem within said channel connected to said movement and detachable means for holding said members in juxtaposition comprising a metallic band adapted to embrace the edges of said members, and means for clamping said band about said members.

7. A watch case comprising, in combination, a pair of non-metallic juxtaposed members, at least one of said members having a recess in the juxtaposed faces, a channel affording communication between said recess and the periphery adapted to receive a stem, each of said members having a projection adjacent the juxtaposed faces, a metallic band surrounding said periphery adapted to engage said projections to retain said members juxtaposed, and means for clamping said band about said member.

JOSEPH B. KISLINGER.
